UNITED STATES PATENT OFFICE.

JOHN F. BANTA, OF GOSHEN, INDIANA.

BED-FRAME CONSTRUCTION.

1,321,183.

Specification of Letters Patent. Patented Nov. 11, 1919.

Application filed April 18, 1918. Serial No. 229,462.

To all whom it may concern:

Be it known that I, JOHN F. BANTA, a citizen of the United States of America, and resident of Goshen, Indiana, have invented a certain new and useful Improvement in Bed-Frame Constructions, of which the following is a specification.

The invention relates to bed-frame corner couplings in general, but more particularly to those for use in coupling an angle-iron side-rail to a wood corner post.

Generally stated, the object of the invention is to provide a novel and improved coupling of this general character.

15 A special object is to provide a novel construction and arrangement whereby the side-rail coupling member may be advantageously made from angle-iron, and securely positioned to the side-rail, and 20 whereby the side-rail-member will detachably engage the post-member without danger of breakage, as will hereafter more fully appear.

To these and other useful ends the invention consists in matters hereafter set forth and claimed, and shown in the accompanying drawings, in which—

Figure 1 is a side elevation of a coupling involving the principles of the invention, 30 showing certain portions in section.

Fig. 2 is a vertical section on line 2—2 in Fig. 1.

Fig. 3 is a horizontal section on line 3—3 in Fig. 2.

35 Fig. 4 is a perspective of the post-member and a portion of the post.

Fig. 5 is a plan of a portion of the side-rail.

As thus illustrated, the invention comprises a corner post 1 of wood or other suitable material, and a post-member consisting of a flat sheet metal plate 2 having outward turned lugs forming hooks 3, these hooks being punched outward from the metal so 45 that a circumscribed opening 4, of the same shape as the hook, is left at the base of each hook. The plate or post-member 2 thus formed is held in place in any suitable manner, as by screws 5 inserted into the post, 50 or by any other suitable means.

The side-rail is of angle-iron formation, having a horizontal or top flange 6 and a vertical or depending flange 7, when the rail is in position for one style of bed frame 55 or bed bottom. The end portion of the side-rail has a slot 8 in the flange 6, and a key

consisting of a vertically disposed strip 9 is inserted in this slot. The side-rail-member 10 is of angle-iron formation, being a short section of angle-iron provided in its 60 end flange 11 with vertically disposed and oval shaped slots 12 to receive the said hooks on the post-member. The outwardly extending vertical flange 13 of the side-rail-member 10 is provided with a horizontally 65 extending slot 14 to receive the flange 6 of the side rail so that flange 7 hangs downward outside against the flange 13 of the side-rail member. With the parts thus assembled, so that the side-rail-member 10 extends above and below the side-rail, rivets 15 are inserted through the strip 9 and also through the flanges 7 and 13, as shown, 70 whereby the strip is secured in place above and below the slot 14, thus forming a reinforce 75 for the flange 13 and materially strengthening the joint formed between the side-rail and the side-rail-member. In this way the side-rail and its side-rail-member are connected together by a strip as well as 80 by the rivets, and a stronger construction is obtained.

It will be observed that the slots 12, like the hooks 3, are disposed in pairs above and below the side-rail and that one hook of 85 each pair is disposed a distance above the other hook of the same pair, so that the hooks of each pair are staggered and the slots have the same arrangement. This is for the purpose of more advantageously distributing the strain, and permits the slots 12 of each pair to be arranged close together, 90 it being observed that these slots as previously stated, are oval, and are thus considerably wider than the hooks—that is to 95 say, the thickness of each hook is considerably less than the width of the middle portion of its allotted slot, so that variation or inaccuracy in the spacing or positioning of the hooks will not prevent them from being inserted through the slots; or, in other words, the hooks can be bent laterally out of their true positions, without interfering with their insertion through the slots when the side rail is coupled to the post; and by 100 positioning one slot somewhat above the other there will be a substantial area of metal at both sides of each slot, and these and other structural advantages are obtained by this construction.

With the oval 110 formation of the slots the hooks are easily inserted therein and withdrawn therefrom,

but the side rail cannot move laterally when the hooks firmly engage the upper ends of the slots, as the upper end of each slot is narrowed to tightly pinch the hook. Of course, the upper ends of all four of the slots are so located that they engage the upper edges of the hooks when the rail settles into place on the post.

From the foregoing it will be seen that a bed frame corner coupling is produced which requires comparatively little work and practically no difficult or expensive operations in the connection of the side-rail to the side-rail member or in the formation of the side-rail-member, both being simply of angle-iron and riveted and keyed together. The post-member is also very simply and economically made from sheet metal by cutting it or punching it into the desired shape.

In the construction shown and described it will be seen that the side-rails of the bed-frame are reversible, as they can be turned up side down, the couplings being of a character to permit this reversibility. As shown, the vertical flange of the side-rail extends downward, but the side-rail can be reversed so that this vertical flange will extend upward, this being necessary at times for a different style of bed or bed bottom.

What I claim as my invention is:—

1. In a bed-frame, a corner post, a side-rail, and a coupling comprising a post-member and a side-rail-member, one member of the coupling being adapted to detachably engage the other, the side-rail-member having a slot to receive the end of the side-rail, and a strip inserted vertically in the side-rail and secured to the side-rail-member above and below said slot.

2. A structure as specified in claim 1, the side-rail being of angle-iron formation, and the side-rail-member being also of angle-iron formation, with one flange of the side-rail resting flatwise against a flange of the side-rail-member, so that the side-rail-member extends above and below the side-rail, and rivets inserted through said strip and side-rail and side-rail-member, the side-rail having a slot for said strip.

3. In a bed-frame corner coupling, a corner post, a side-rail formed with a slot, a vertically disposed side-rail member extending above and below the rail and adapted to detachably engage the post, a strip inserted vertically in the slot of the side-rail, means on the side-rail-member above and

below said slot to engage said strip to hold the side-rail-member in position on the end of the side-rail, and means to support the side-rail-member on the post.

4. In a bed frame, a coupling for the end of a side-rail, comprising a vertical section of angle-iron having a notch in one flange thereof, an angle-iron side-rail having its end adapted for insertion in said notch, with a slot in the side-rail end portion, a strip for insertion in said slot, and means on the vertical section to engage said strip, so that the side-rail will be locked in said notch, and with one flange of the side-rail outside of the vertical section.

5. In a bed-frame, a coupling for the end of a side-rail, comprising a side-rail end-portion having a slot, a strip inserted vertically in said slot, and means coöperating with said strip to removably hold the side-rail in position, with a flange of the side-rail extending outside of said means.

6. In a bed frame, a corner coupling comprising a vertical section of angle iron having a horizontal notch in one flange thereof, an angle iron side rail formed to enter said notch and abut against the other flange of said vertical section, with one flange of the rail disposed outside of the notched flange of the section, and means to retain the section and rail in interlocked relation.

7. In a bed frame, a corner coupling comprising a vertical section of angle iron, an angle iron side rail, the rail and one flange of the section being formed to interlock with each other and with the end of the rail against the other flange of the section, and with one flange of the rail outside of said one flange of the section, and means to retain the rail and section in interlocked relation.

8. A structure as specified in claim 6, said means comprising a vertical member inserted in the horizontal flange of the side rail, and elements on the section to engage said member and thereby hold the side rail in place.

9. A structure as specified in claim 7, said means including a slot in the side rail, a member inserted in said slot, and means on the section to engage said member to hold the side rail in said notch.

Signed by me at Goshen, Indiana, this fourth day of April, 1918.

JOHN F. BANTA.
